L. MARTIN & J. L. JONES.
PENCIL HOLDER.
APPLICATION FILED APR. 22, 1914.

1,134,691.

Patented Apr. 6, 1915.

UNITED STATES PATENT OFFICE.

LILITH MARTIN AND JESSIE L. JONES, OF ANDERSON, INDIANA, ASSIGNEES TO GEORGE S. MARTIN AND MAX BERGER, BOTH OF ANDERSON, INDIANA.

PENCIL-HOLDER.

1,134,691.

Specification of Letters Patent.

Patented Apr. 6, 1915.

Application filed April 22, 1914. Serial No. 833,737.

To all whom it may concern:

Be it known that we, LILITH MARTIN and JESSIE L. JONES, citizens of the United States, and residing at the city of Anderson, in the county of Madison and State of Indiana, have invented certain new and useful Improvements in Pencil-Holders, of which the following is a specification.

This invention relates to pencil holders designed to support a pencil or other writing device suspended above the top of a table, desk or other surface, and more particularly a holder having a flexible stem from which is suspended a clasp which carries the pencil, and which stem is free to yield in any direction so that the pencil may be lowered into position for use, and when released is swung back to elevated position by the stem assuming its normal, erect position.

It is the object of the invention to provide in a device of the kind stated a novel support and attachment for the pencil clasp, which enables the pencil to be freely operated in any position. This object is attained by means of a combination and arrangement of parts to be hereinafter described and claimed, reference being had to the accompanying drawing in which—

Figure 1 is a side elevation of the device; Fig. 2 is a section on the line 2—2 of Fig. 1, and Fig. 3 is a perspective view showing a modified base structure.

Referring specifically to the drawing, 10 denotes a suitable base block of sufficient weight to support the pencil holding device, and to serve as a paperweight. The bottom of the base is covered with a sheet of felt or other suitable material 11 to prevent scratching the desk, table or other surface on which the base is placed. The sheet is cemented or otherwise secured to the base, and the latter may be of any design or shape, and finished in any suitable manner. In the top of the base, at the center thereof, is an aperture into which is pressed a small tube 12, which may be a piece of seamless brass tubing finished in the same manner as the base. This tube supports a flexible stem 13 composed of a coil of wire, and carrying a chain 14, or other suitable suspension device, to which a clasp 15, carrying a pencil 16, is attached. The convolutions of the coil are brought closely together throughout the entire length of the stem, except at its upper

end, where they are separated and the stem is bent to a lateral curve, as indicated at 17. The stem normally extends erect or perpendicularly from the base, but as it is flexible it may be bent sidewise and when released it springs back to erect position, lifting with it the chain 14 and the parts carried by the latter. The chain is attached to the upper curved extremity of the stem, by a means to be presently described, in view of which the pencil hangs free and away from the stem. The lower end of the stem is inserted and held in the tube 12, and it takes all the tension and strain without the aid of any reinforcements. Over the curved extremity 70 of the stem is slipped and held a small sleeve 18. The inner end of the sleeve is pressed slightly together as indicated at 19 to grip the part 17, and its outer end is also pressed inward to form an internal annular 75 flange 20 which is spaced slightly from the extremity of the part 17 to accommodate a small disk or washer 21, the same being loosely mounted in the sleeve between the flange 20 and the extremity of the part 17 80 so as to be free to rotate. To the center of the disk 21 is attached the chain 14. The pencil holder 15 carried by the chain is designed to accommodate different sized pencils or pen holders. As the disk 21 is rotatable, the chain and the parts carried thereby operate freely in any direction. The disk also conceals the extremity of the stem. The holder 15 has an eye 22 for attachment 85 of the chain.

The parts herein described will be given a nickel, copper, brass or other desired finish.

Fig. 3 shows a slightly modified structure. A clamp 23 is substituted for the base 10, for securing the device in position for use. 95 The stem 13 holds the pencil or other writing device suspended above the top of the table, desk or other surface, and upon grasping the pencil for writing therewith, the stem, by reason of its flexibility, bends over 100 as shown dotted in Fig. 1, and allows the pencil to be used. Upon releasing the pencil, the stem swings back to its normal erect position.

We claim:

1. A pencil holder comprising a base, a normally erect flexible stem rising from the base, a sleeve fitting over the extremity of the stem and frictionally held thereon, a disk loosely rotatably mounted in the sleeve, a 110

suspension device connected to the disk, and a pencil clasp carried by the suspension device.

2. A pencil holder comprising a base, a normally erect flexible stem rising from the base, a sleeve fitting over the extremity of the stem and frictionally held thereon, said sleeve having an internal annular flange at its outer end, which flange is spaced from the extremity of the stem, a disk loosely mounted in the sleeve between the flange and

the extremity of the stem, a suspension device connected to the disk, and a pencil clasp carried by the suspension device.

In testimony whereof we affix our signatures in presence of two witnesses. 15

LILITH MARTIN.
JESSIE L. JONES.
